(57) **CLAIM**

The ornamental design for a clip for a clamshell griddle, as shown and described.

DESCRIPTION

FIG. 1 is a front perspective view of a clip for a clamshell griddle;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a perspective view of the clip for a clamshell griddle being used in conjunction with a clamshell griddle. The broken lines showing environment form no part of the claimed design.
